UNITED STATES PATENT OFFICE.

EDWARD HALL, OF RUTHERFORD, NEW JERSEY, ASSIGNOR TO JERSEY CITY PRINTING COMPANY, OF JERSEY CITY, NEW JERSEY, A CORPORATION OF NEW JERSEY.

PLURAL-IMAGE DEVICE.

1,218,082.

Specification of Letters Patent.

Patented Mar. 6, 1917.

Application filed June 1, 1915. Serial No. 31,379.

To all whom it may concern:

Be it known that I, EDWARD HALL, a citizen of the United States, residing in Rutherford, county of Bergen, State of New Jersey, have invented certain new and useful Improvements in Plural-Image Devices, of which the following is a specification.

My invention relates to means for causing one of two or more superimposed images to become substantially invisible, at the same time making the temporarily desired image more striking to the eye. My device is applicable to a wide variety of uses and particularly for educational, advertisement and amusement purposes.

In the accompanying drawings which form a part of this specification, Figure 1 is a perspective view of one embodiment of my invention; Fig. 2 is a vertical sectional view 20 of the construction of Fig. 1; Fig. 3 is a view similar to Fig. 2 showing a modification; Fig. 4 is a diagrammatic view of one side of the image tape or belt utilized in the construction of Fig. 3; Fig. 5 is a view similar 25 to Fig. 4 showing a different portion of said tape or belt; Fig. 6 is a view similar to Fig. 2 showing a further modification; Fig. 7 is a partially diagrammatic vertical sectional view of a further modification; Fig. 8 is a front elevation of the construction shown in Fig. 7, and Fig. 9 is a view similar to Fig. 2 showing a still further modification.

Referring to the drawings in detail, the numeral 1 designates a box in the front of which is an aperture 2, in which is mounted an image screen 3. This screen is provided with a plurality of superimposed images, the separate images being depicted in contrasting colors such as red and blue. This screen or plate is transparent or translucent, and in case it is transparent one image may be formed on one surface 4, while the other image may be formed on the opposite surface 5. For purposes of illustration I have shown these images to be a boy 6 and a yacht 7. The picture of the boy may be in blue and that of the yacht in red, the glass or other medium forming the background for the screen preferably being colorless. In 50 the interior of the box are mounted three rollers, 8, 9 and 10, over which passes the endless belt 11. The roller 10 is driven by the belt 12 from any suitable source of power, such as the motor 13. Also mounted 55 within the box and behind one lap of the

tape or belt is a source of light 14 which may be an incandescent electric lamp, and a reflector 15 adapted to cause powerful light rays to pass through that portion of the tape or belt adjacent to the image screen, and 60 after passing through the tape or belt to illuminate the image screen.

The belt 11 is composed of two halves joined as shown at 16 and 17, one-half of the belt, for example the upper half in Figs. 1 65 and 2, is made of any suitable flexible translucent or transparent material and may be colored red, as indicated by the vertical lining in Fig. 1. The lower half of the belt may be constructed as indicated in these 70 figures of any suitable flexible translucent or transparent material and may be colored blue, as indicated by the horizontal lines in Fig. 1.

It will be obvious from the construction 75 above described that the portion of the belt which is colored blue and which at any time may be situated between the source of light and the image screen will cause blue light to shine through the screen, and, similarly, the 80 red portion of the tape or belt which is between the source of light and the image screen will cause red light to shine through the adjacent portion of the screen.

When blue light is caused to shine through 85 the plate, an observer looking at the plate through the aperture 2 will see that portion of the image which is depicted in red and it will appear to him as substantially black upon a blue background. Simultaneously, 90 the image which is depicted in blue will become substantially invisible, having merged into the general blue tone cast upon the background. In a similar manner, when red light is caused to shine through the image screen, that portion of the picture which is depicted in blue will appear to the observer in black against a red background into which has merged the red portion of the picture because of the red hue cast upon 100 the background by the red light passing through the screen. The appearance of the contrasting color as black in each case, is due to the well-known fact that the pigment or other material which appeared 105 blue by transmitted light has this property because it shuts off all rays except blue, and therefore will effectually bar the passage of the red rays, resulting in an impression of black upon the eye. The same 110

principle holds with respect to the blue light transmitted through the red coloring matter.

The general result of the operation above described will be to cause an alternation in the pictures seen. As clearly indicated in Fig. 1, the figure of the boy will appear whenever red light is transmitted through the screen, and the picture of the yacht will be seen when the blue light is transmitted through the screen, thus causing a dissolving view of an extremely novel effect without projecting the images.

In Figs. 3, 4 and 5 I have illustrated a modification in which an endless translucent belt 18 passes over rollers 19, 20, 21 and 22. This belt corresponds to the image screen 3, excepting for the fact that it is flexible and contains a plurality of superimposed pictures 23 and 24 of contracting colors illustrated in Figs. 4 and 5. These pictures may be either directly superimposed upon the same surface or may be placed upon opposite surfaces 25 and 26 in the case the belt is transparent and not merely translucent.

The roller 22 is driven from the motor 27 by means of gears 28, 29, 30 and 31 which form part of an intermittent motion by which the uniform rotation of the shaft of the motor 27 is changed into an intermittent rotation of the roller 22. For purposes of illustration I have shown the well-known Geneva motion, which need not be described in detail, but any other suitable mechanism for achieving this intermittent transmission of rotation may be substituted, as will be obvious.

Upon the shaft of the gear 29 is mounted a disk 32 carrying a segmental contactor 33 which passes under the brush 34 forming part of the electrical circuit 35, 36, of which a source of red light 37 is a part. The mechanism is so proportioned that during the intervals of rest of the roller 22 the segmental contactor 33 will pass under and in contact with the brush 34, so as to form a complete electrical circuit through the lamp or other source of illumination, causing red light to shine through the tape. Therefore, during the periods when the lamp is dark the tape will be moved to a predetermined distance equal to the length of a picture. After the tape has come to rest, the lamp will automatically flash during one-half the interval of rest of the tape.

If the images 23 and 24 are superimposed as in the case of the construction of Figs. 1 and 2, but the blue picture is of a pale tint, it will be practically unnoticeable when the lamp 37 is dark and the image is viewed by reflected natural or artificial light from the outside of the box. However, when the lamp flashes and red light is projected through the screen, the blue picture

will stand out black, or substantially so, against a red background into which the red picture has merged because of its similar tint. The result, so far as the observer is concerned, will be similar to that produced by the construction first described.

In Fig. 6 I have illustrated a modification wherein a second source of illumination 38 is provided, so that no reliance is placed upon daylight or other means of illumination normally existing outside of the box. The structure is otherwise the same except for the fact that two brushes, 39 and 40, diametrically arranged with respect to the segmental contactor 33, are now provided. Wire 41 leads from the brush 39 to the lamp 37, from which the wire 42 leads to the source of electrical energy 43, the circuit being completed through the wire 44 leading to the segmental contactor. Wire 45 leads from the brush 40 to the lamp 38, which is in turn connected by the wire 46 to the wire 42 at the point 47, the remaining portion of the wire 42 serving as a conductor to the source of electrical energy. By this arrangement it will be seen that instead of a single light alternately flashing and remaining dark through one-half of the period of rest of the ribbon or screen, the lights will alternately flash, one or another of the two lights always being lighted during the period of rest of the ribbon or screen. In the case of this modification the light 38 may preferably be blue in color in order to make the cutting out of the blue picture more certain, and in this case the original tint of the blue picture may be bolder.

Fig. 7 illustrates a modification in which the box 48 is provided with a substantially central partition 49 and with an aperture 50 in one side. In the partition is mounted a screen or plate 51 of transparent material such as glass, upon which is inscribed a picture 52, preferably in blue. In back of the screen is a shelf 53 on which may be placed any suitable article such as the clock 54, which it is desired to show in connection with the picture on the screen. The hinged door 55 permits the replacement of this article as desired. In front of the screen is mounted a red lamp 56, and behind the screen but in front of the clock or other object to be shown is placed a blue lamp 57. A source of electric energy 58 supplies current to these lights in alternation, the path of the current being through the wire 59 to the segmental contact 60 on the disk 61, which is constantly rotated by any suitable source of power. From the contact 60, when the parts are in the position shown in Fig. 7, the current passes through the brush 61^a, wire 62, the lamp 56, and thence back to the source of energy by the wire 63. When the segment is in contact with the other brush

64, the current will pass through the wire 59, segment 60, brush 64, wire 65, lamp 57, wire 66, and wire 63.

When the red light 56 is lighted and the blue light 57 is dark, an observer looking through the aperture 50 will see the picture 52 upon the screen. This picture will appear substantially black, since the blue coloring matter has the property of reflecting only blue rays of light. The background will be colored red by the light 56, and the clock 54 or other object will not be seen, because the flooding of the screen with the red light from the front will act to prevent the observer seeing the unilluminated object behind the screen. When, however, the blue light 57 is lighted and the red light 56 is extinguished, the object 54 will be seen by the observer, for the reason that the blue picture 20 on the screen will then merge into the general blue tone given to the screen by the light, and the object, now being strongly illuminated, will be visible through this light blue tint of the screen. If a picture such as that shown in Fig. 8 is depicted upon the screen, the observer will alternately see the picture and the object, and a relation of cause and effect useful in advertising and other purposes, as will be obvious, may be produced.

In Fig. 9 I have illustrated a modification which is in many ways an extension of the idea embodied in the form of apparatus shown in Figs. 3 to 5, inclusive. In this type the box 67 is provided with an aperture 68, behind which is rotated the belt 69 carried by the pulleys 70, 71, 72 and 73. Immediately behind the belt 69 is a second belt 74 carried on the rollers 75, 76, 77 and 78. One of these belts is provided with a series of pictures in blue, while the other is provided with a series of pictures in red, so that the two belts taken together correspond to the single belt illustrated in Figs. 4 and 5. The belt 69 is driven by the pulley 72 through an intermittent motion 79 from the motor 80. The belt 74 is similarly driven by an intermittent motion 81 from the same motor. I have illustrated the well-known Geneva motion, but it will be obvious that any other suitable motion may be substituted. The gearing is so proportioned that the belts move intermittently but in synchronism and at the same rate of speed, so that although the belts are of different length the pictures on the two belts immediately behind the aperture 68 will always register, that is, will be in alignment so far as their centers or borders are concerned. Since the belt 74 is much shorter than the belt 69, at the end of a complete revolution of the belt 74, the first picture on the belt 74 will not register with the first picture on the belt 69, but with some other picture, so that the duplication of pairs of pictures will be effected

only at long intervals, depending upon the number of pictures on each belt, and consequently upon the lengths of the belts. There is mounted within the box means for illuminating the pictures in register, including a red light 82 and a blue light 83, which are lighted in alternation from any suitable source of electrical current 84 by means of a flasher 85 which may be similar to those already described, except that the rotating segmental contact 86 is substantially less than 180 degrees in angular length and is made sufficiently short so that neither light is lighted during the period when the belts are being advanced to bring a new pair of pictures before the aperture.

While I have described my invention throughout in connection with red and blue colors for the contrasting images, it is obvious that other sets of contrasting or primary colors may be utilized, although I regard the red and the blue as most advantageous owing to the fact that they lend themselves readily to printing and other methods of producing images of the character described.

While I have illustrated and described only certain embodiments of my invention, I realize that it is susceptible of wide application, and I do not desire to be limited to the precise structure shown and described.

Having thus described my invention, I claim:

1. In a device of the character described, a translucent flexible tape carrying superimposed separate images of contrasting colors thereon, and means for causing one of said images to become substantially invisible by projecting a light of the same color through said tape. 100
2. In a device of the character described, a translucent flexible tape carrying contrastingly colored separate images on opposite faces, and means for causing said images to become alternately visible by projecting a light therethrough and varying the character of said light to correspond with the distinctive color of each image in turn. 110
3. In a device of the character described, a transparent support, a colored image upon said support, an object behind said image, and means for causing said image to become substantially invisible by projecting a light of the same color through said support. 115
4. In a device of the character described, a transparent support, a colored image upon said support, an object behind said image, and means for causing said image to become substantially invisible by projecting a light of the same color through said support and simultaneously illuminating the object thereby. 120
5. In a device of the character described, a translucent support, a colored image on said support, a second contrastingly colored 130

- image in juxtaposition to the first image, and means for causing a colored light of substantially the same tone as one of the images to shine through both of said images.
5. In a device of the character described, a translucent support, a colored image on said support, a second contrastingly colored image in juxtaposition to the first image, and means for projecting through both of said images, in alternation, colored lights having substantially the same tone as that of the respective images.
10. In a device of the character described, a support, a colored image thereon, a second contrastingly colored image in juxtaposition to the first image, means for moving said support, and means for causing a light of substantially the same tone as that of one of the images to shine through both of the images.
15. In a device of the character described, a support, a colored image thereon, a second contrastingly colored image in juxtaposition to the first image, means for moving said support, and means for causing a light of substantially the same tone as that of one of the images to shine through both of the images only during intervals of rest of said support.
20. In a device of the character described, a support, a colored image thereon, a second contrastingly colored image in juxtaposition to the first image, means for moving said support, and means for causing a light of substantially the same tone as that of one of the images to shine through both of the images only during intervals of rest of said support.
25. In a device of the character described, a support, a colored image thereon, a second contrastingly colored image in juxtaposition to the first image, means for intermittently moving said support, and means for projecting through both of said images, in alternation, colored light corresponding in tone to the respective images.
30. In a device of the character described, a support, a colored image thereon, a second contrastingly colored image in juxtaposition to the first image, means for intermittently moving said support, and means for projecting through both of said images, in alternation, colored light corresponding in tone to the respective images.
35. In a device of the character described, a support, a colored image thereon, a second contrastingly colored image in juxtaposition to the first image, means for causing both images to move simultaneously and intermittently, and means for projecting a colored light of substantially the same tone as one of the images through both of the images only during intervals of rest of said images.
40. In a device of the character described, a support, a colored image thereon, a second contrastingly colored image in juxtaposition to the first image, means for causing both images to move simultaneously and intermittently, and means for projecting a colored light of substantially the same tone as one of the images through both of the images only during intervals of rest of said images.
45. In a device of the character described, a support, a colored image thereon, a second contrastingly colored image in juxtaposition to the first image, means for simultaneously and intermittently moving said images, and means for projecting through both of said images, in alternation, colored light corresponding in tone to each of the images.

EDWARD HALL.
